United States Patent

Des. 236,405
Patented Aug. 26, 1975

236,405

GOBLET OR SIMILAR ARTICLE

James Lloyd Thrush, Lancaster, Ohio, assignor to Anchor Hocking Corporation, Lancaster, Ohio

Filed Sept. 20, 1973, Ser. No. 399,134

Term of patent 14 years

Int. Cl. D7—01

U.S. Cl. D7—13

FIG. 1.

FIG. 2.

FIG. 8.

FIG. 1 is a side elevational view of a goblet or similar article showing my new design in the size and proportions of a water goblet;

FIG. 2 is a top view thereof;

FIG. 3 is a bottom view thereof;

FIG. 4 is a sectional view taken along line 4—4 of FIG. 1;

FIG. 5 is a side elevational view of a goblet or similar article showing my new design in the size and proportions of a snifter;

FIG. 6 is a side elevational view of a goblet or similar article showing my new design in the size and proportions of a wine goblet;

FIG. 7 is a side elevational view of a goblet or similar article showing my new design in the size and proportions of an old fashioned goblet; and

FIG. 8 is a side elevational view of a goblet or similar article showing my new design in the size and proportions of a champagne goblet.

I claim:

The ornamental design for a goblet or similar article, substantially as shown and described.
